(57) **CLAIM**

The ornamental design for a computer having a door, as shown and described.

DESCRIPTION

FIG. 1 is a front perspective view of an embodiment of the design for the computer having a door, wherein the door has a first series of perforated horizontal panels separated by a first series of non-perforated horizontal bars, the first series of non-perforated horizontal bars has a non-illuminable left portion and an illuminable right portion, and the door is illustrated in a closed or latched position with respect to a chassis of the computer;

FIG. 2 is a front view of an embodiment of the design for a computer having a door;

FIG. 3 is a rear view of an embodiment of the design for the computer having a door, wherein a central rear portion of the computer has a second series of perforated horizontal panels separated by a second series of non-perforated horizontal bars;

FIG. 4 is a left side elevational view of an embodiment of the design for the computer having a door, wherein a front side and a rear side of the computer taper inwardly from a top side to a bottom side;

FIG. 5 is a right side elevational view of an embodiment of the design for the computer having a door, wherein the front side and the rear side of the computer taper inwardly from the top side to the bottom side;

FIG. 6 is a top plan view of an embodiment of the design for the computer having a door;

FIG. 7 is a bottom plan view of an embodiment of the design for the computer having a door;

FIG. 8 is a front perspective view of an embodiment of the design for the computer having a door, wherein the door is illustrated in an open or unlatched position rotated partially away from the chassis of the computer, a modular component is illustrated with a latch/release handle having a horizontal axis of rotation; and,

FIG. 9 is a front view of an embodiment of the design for the computer having a door, wherein the door is illustrated in the open or unlatched position rotated partially away from the chassis of the computer.

In these drawings, the solid lines illustrate the claimed ornamental design, whereas the broken lines illustrate environmental features that form no part of the claimed ornamental design.
